TRAIN DISPATCHING SYSTEM FOR RAILROADS

Filed Sept. 21, 1927

UNITED STATES PATENT OFFICE

SEDGWICK N. WIGHT, OF ROCHESTER, NEW YORK, ASSIGNOR TO GENERAL RAILWAY SIGNAL COMPANY, OF ROCHESTER, NEW YORK

TRAIN-DISPATCHING SYSTEM FOR RAILROADS

Application filed September 21, 1927. Serial No. 221,036.

This invention relates in a general way to railway signaling systems, and more especially to standard absolute-permissive-block signal systems and the tumble-down circuits as used in conjunction with such systems.

To those skilled in the art of railway signaling, and particularly A. P. B. circuits for single track signaling, it is readily understood how a train leaving a passing siding 10 immediately sets all opposing signals to danger, thereby preventing any trains from advancing, off the next passing siding in advance, and into the intervening single track section. This feature is disadvantageous, 15 in that, a train switching at a siding may hold up traffic from the next siding unnecessarily, thus cutting down the efficiency of the road.

At the same time this tumble-down feature is one that cannot be wholly eliminated 20 because of its value to the safety of the system.

With the foregoing and other important considerations in mind, it is proposed in accordance with the present invention to provide the necessary protection for a train switching at a passing siding without unnecessarily delaying traffic moving toward such siding. Generally speaking, it is proposed to at times allow a train the use of a passing siding and one automatic block beyond in either 25 direction, and at the same time permit a train to proceed from the next passing siding to approach within a safe distance of the train engaged in switching. This act of at times allowing the train to make switching moves 30 beyond the limits of the usual passing siding without interfering with a train entering the opposite end of the single track section in which the first mentioned train is making such switching moves, is for convenience 35 called "intercepting the tumble-down circuit". This because the tumble-down circuit has actually been made shorter. Generally speaking this intercepting of the tumble-down circuit is preferably accomplished by 40 having a member of such switching crew operate a suitable manual operable device located near the switch at which such switching moves are made, which if operated intercepts the tumble-down circuits and holds the signals associated with that track switch and one

block or braking distance therefrom at stop. In one form of the invention, which form has been specifically illustrated in the accompanying drawing, a suitable dual control selector is used for this purpose, whereby the 55 track switch may be connected for manual operation by a switch stand or for mechanical operation by a power-operated switch machine, depending on the position of this dual control selector; suitable contacts being 60 associated with this dual control selector whereby the tumble-down circuit is interrupted when the dual control selector is positioned for switch stand operation, and the tumble-down circuit extends throughout the 65 entire single track section when the dual control selector is positioned for switch machine operation.

More specifically, the present invention contemplates the use of a selecting relay located adjacent the first pair of intermediate signals in the single track section which relay if in one position holds the intermediate signal for approaching traffic at stop and arranges the tumble-down circuit so that a train 70 in the block between the siding and such first pair of intermediate signals will not interrupt the tumble-down circuit and will therefore permit a train to enter from the opposite end of the single track section. This 75 relay is preferably so connected that it cannot pick up unless traffic conditions in the single track section are clear, or there is at least no departing train moving the first block of the single track section, and which relay if once picked up will remain stuck up until the dual control selector is moved to its normal switch machine position.

Other objects, purposes and characteristic features of the invention will appear as the 80 description thereof progresses.

In describing the invention in detail reference will be made to the accompanying drawing, which is a diagrammatic view of a standard A. P. B. system modified in accordance with this invention.

Referring to the drawing there is shown the east end of siding SD with its attendant track switch TS, the connecting single track section O and the west end of siding SD¹ with 100

its attendant track switch TS¹. The track including the sidings, is provided with insulated track section *a*, *b*, etc., in a manner well known to those skilled in the art. The track batteries are conventionally shown, and the track relays for these various track sections are, for convenience, indicated conventionally by dotted lines. The track sections *a* and *b* are detector track sections at the ends of the sidings, the circuits of which are suitably cross-bonded, in a well known manner, at the switch points.

The signals which may be of any suitable type, are conventionally shown as of the semaphore type, and are designated, 1, 1^d, 2, 2^d, 3, 4, 5, 6, 7, 7^d, 8 and 8^d. The signals 1 and 1^d govern west bound traffic onto the main track opposite the siding SD and into the siding, respectively, and are conveniently termed entering signals. The signals 2 and 2^d govern the east bound traffic off the main track opposite the siding SD and out of the siding, into the single track stretch O. These signals are called, for convenience, the east bound starting signals. The stretch of single track O is preferably provided with opposite intermediate signals, as shown, or with staggered intermediate signals in accordance with A. P. B. standard practice. Four intermediate signals, 3, 4, 5 and 6 are shown. These intermediate signals are of the permissive type, as shown conventionally with a pointed blade. Signals 7 and 7^d are the west bound starting signals for siding SD¹, and signals 8 and 8^d, entering signals. All entering and starting signals are of the stop-and-stay type as indicated by their square-ended blades.

All of these signals, except the take-siding signals 1^d and 8^d, are preferably three-position signals, and governed in accordance with the condition of their associated polar home relays H (as indicated by the polar contacts) having a prefix corresponding to the reference number of the signal, as described in my prior Patent No. 1,294,736, dated February 18, 1919. A particular starting signal can of course only clear in accordance with the condition of its home relay when the track switch assumes the position corresponding to such signal. The take-siding signals are preferably controlled only in accordance with the position of the track switch and the associated detector track relay.

In order to simplify the drawing, the only circuits and relays shown are those of a standard A. P. B. system necessary to illustrate the present invention in one form, and with the invention applied for facilitating traffic during the switching of a train in the vicinity of track switch TS only.

The track switch TS is shown conventionally operated through a dual switch control selector DS by either an electric switch machine SM controlled from an interlocking tower or in accordance with a train dispatch-

ing system, or by a hand-thrown switch stand SS of the usual construction.

To describe the present invention clearly it will be necessary to briefly consider the usual operation of an absolute-permissive-block system of the type shown. Therefore, the description of such operation will not be complete in all its details.

To simplify the wiring diagram and the explanation, positive, negative and common wires from a suitable source of energy, as for example a storage battery, have been indicated by the symbols B, N and C respectively, and BN is to indicate positive or negative.

For the purpose of illustration it will be well to consider the passing of an east bound train off the siding SD onto the single track section O. When the train enters the track section *b* the track relay is deenergized which acts to deenergize the relay 3H through a circuit which is obvious from the drawing. This action continues down the line through a tumble-down circuit (well known to those skilled in the art), and results in setting all opposing signals, such as 3, 5 and 7, to the stop position, thereby preventing an opposing train from entering the opposite end of the single track section O. This feature is desirable for protecting a train moving from siding SD toward siding SD¹, but it is very undesirable for a train that is only switching in the vicinity of the track switch TS of siding SD. This undesirable feature can be eliminated in accordance with the present invention without interfering with safety in a manner as presently described.

At the signal 3 is located an extra stick relay XS, the purpose of which is to set the signal 3 in the stop position and prevent a complete tumble-down due to a train in track section *b* or *c*. The control circuit for this relay, assuming the dual control selector to be in the position for switch stand operation, is readily traced as follows:—starting at a suitable source of energy B, dual selector contacts 9 in the reverse or dotted position, wire 10, winding of the XS relay, wire 11, wire 12, and either of the following two branches (1) wire 13, and a front contact 14 of the relay 3H to a common return wire C, or (2) wire 15, and a front contact 16 of the usual directional stick relay 4S to the common return wire C. Once relay XS is energized it is stuck up by the following circuit:—source of energy B, dual selector contact 9 in the reverse or dotted position, wire 10, winding of the relay XS, wire 11, wire 17 and a front stick contact 18 of the relay XS to C. This stick circuit can only be broken by returning the dual control selector handle to normal, as shown.

With the dual selector in the normal position, the energizing circuit for the 3H relay is as follows:—source of energy B, selector contacts 9, wire 19, front contact 20 of the

detector track relay DTA, wire 21, front contact 22 of the track relay TB, wire 23, front contact 24 of the track relay TC, wire 25, back contact 26 of the relay XS, wire 5 27, winding of the relay 3H to C.

Operation.—A train crew desiring switching privileges will ordinarily first call the dispatcher and upon obtaining permission will place the dual selector in the reverse position enabling the switch to be hand-operated by the switch stand SS. This movement places the selector contact 9 in the dotted position, the result of which is to de-energize the relay 3H by reason of opening of the circuit therefor previously traced, and otherwise obvious. At the same time the selector contact 9 will complete the energizing circuit, as traced above, for the relay XS, providing there is no east bound train between signals 10 2 and 4 in the single track section O which has already de-energized relay 3H. In this connection it should be understood that by reason of the delay in dropping of contacts or relay 3H, the relay XS will be picked up before 15 relay 3H actually drops. The energization of relay XS will result in setting signal 3 at danger or stop, and in preventing a further tumble-down, such as ordinarily occurs. Ordinarily when relay 3H becomes deenergized 20 it will in turn de-energize the relay 5H through opening of contacts 28 of the following circuit:—source of energy BN (meaning positive or negative depending on whether the signal 3 is at proceed or danger), front 25 contact 28, of the relay 3H, wire 29, wire 30, wire 31, back contact 32 of the relay 4S, wire 33, front contact 34 of the track relay TD, wire 35, front contact 36 of the relay TE, wire 37, winding of the relay 5H to C. With 30 the home relay 5H assuming the retracted position, it will in turn deenergize relay 7H by opening contacts 38 of the following circuit:—source of energy BN, front contact 38 of the relay 5H, wire 39, wire 40, back 35 contact 41 of the relay 6S, wire 42, front contact 43 of the track relay TF, wire 44, front contact 45 of the track relay TG, wire 46, front contact 47 of the detector track relay DTH, wire 48, winding of the relay 7H to C. It is thus seen that with relay XS in its 40 retracted condition the entrance of an east-bound train in section b causes all westbound signals 2, 3 and 6 to assume the stop position. On the other hand, when relay 3H is deenergized by reason of shifting selector contact 9 to the dotted position, and relay XS is energized in response to this shifting of contact 45 9 as heretofore described, this change in the condition of energization of relays 3H and XS shifts the source of energy for the circuit of relay 5H, from relay 3H to relay XS, which control for supplying a new circuit may be traced as follows:—source of energy BN (plus or minus), front contact 49 of the

relay XS, wire 50, wire 30, etc. as previously traced, through relay 5H to C.

The train in question is therefore allowed to switch as far as to signal 3 without interrupting the tumble-down circuits and unnecessarily delaying westbound traffic in the single track section O, at the same time providing adequate protection for trains in the rear by means of signals 2 and 2^a controlled by relay 2H. The circuit for relay 2H may be traced as follows:—source of energy BN, front contact 51 of the relay 4H, wire 52, wire 54 (or BN, front contact 65 of the relay 4S, wire 66 connecting to wire 54) back contact 55 of the relay 3S, wire 56, back contact 57 of the relay XS, wire 58, front contact 59 of the track relay TC, wire 60, front contact 61 of the track relay TB, wire 62, front contact 63 of the detector track relay DTA, wire 64, winding of the relay 2H to C. During switching maneuvers, this circuit is broken at the back contact 57 of the relay XS, thereby keeping signals 2 and 2^a in the danger position due to de-energization of relay 2H.

On returning the dual selector to normal 90 the original tumble-down circuits are restored through selector contact 9. It is of course understood that although the invention has been shown applied to the switch TS only, it may also be applied to the switch TS¹ 95 and may be applied to each end of every single track section, if desired.

It is thus seen that in the modified A. P. B. system illustrated, one embodiment of the present invention, the tumble-down circuit for putting all of the westbound signals in their stop position normally extends from the signal 2 to the signal 8, but if the dual control selector DS is in the abnormal switch stand position, this tumble-down circuit extends only from the signal 4 to the signal 8. The ability to intercept the tumble-down circuit, so to speak, by the means described, enables a switch engine to make switching moves on such track sections as a and b without in any way interfering with the entering of a train at the opposite end of the single track section O. If a train does enter the opposite or east end of the single track section O when the tumble-down circuit is intercepted, that is the relay XS is energized, this train will encounter the signal 5 at caution and will be brought to a stop at the signal 3 so that this train is safeguarded against encountering the switching engine at speed. When the dual control selector is returned to its normal switch machine position the stick relay XS is de-energized and the circuit arrangement for the signals functions in exactly the same way as that of an A. P. B. system to which the invention is not applied.

At first hand it would appear that the relay XS might, with safety, be controlled directly by the contact 9 of the dual control selector. Although this could be done it is not 130

deemed quite safe, because under certain operating conditions two trains could enter opposite ends of the single track section O simultaneously with a possibility of a collision. 5 For instance, if an eastbound train had just entered the single track section O, and the engineer of the switching engine were to operate the dual control selector DS associated with switch TS to the dotted switch stand position the starting signals 7 or 7^d at the east end of this single track section O would remain at proceed until the eastbound train passes the signal 4 and in so doing interrupts the tumble-down circuits, which place the signals 5 and 7 or 7^d to stop. In other words, 10 during the time that the eastbound train moved from signal 2 to signal 4, with the dual control selector DS in the switch stand position, a westbound train can enter the single track section O and obviously the eastbound and westbound train could not pass each other and one of them would be required to back out. The possibility of two trains entering 15 opposite ends of the single track section does not only interfere with facility of train movement, but could possibly endanger the two trains moving toward each other in the single track section. If the relay XS, however, 20 is controlled in a manner as already described, and as shown in the drawing, this relay XS would not pick up in response to operation of the dual control selector DS to the dotted position during the time that there is an eastbound train moving on track sections a, b, or 25 c, because the relay 3H is deenergized under this condition thus leaving its contact 14 open, and the usual directional stick relay 4S of the signal 4 is still in its deenergized position, thus leaving its contact 16 open, so that 30 the circuit for the relay XS is incomplete until the eastbound train in question has passed the signal 4, and in so doing has picked up the directional stick relay 4S. In this connection, 35 it should be noted that the relay 3H is normally energized and if the dual control selector DS is moved to the switch stand position with no trains in the single track section O, the stick relay XS is picked up by reason of the fact that relay 3H is up, and 40 with the relay XS once picked up it is stuck up through its stick contact 18, and will remain up in spite of the immediate de-energization of the relay 3H thereafter, due to shifting of the dual control selector contact 45 9 and opening of contact 26 of relay XS. In this connection, the relay 3H may be made slow to drop, or the contact 14 may be a slow opening contact or may be one of the slow acting repeater relays operated by the relay 50 3H, in order to allow relay XS sufficient time to pick up before contact 14 opens. Further, if the east bound departing train just mentioned has actually nosed by signal 4, but is still on the track circuit c, the stick relay 4S 55 will have been picked up for obvious reasons,

and if the dual control selector is at this time operated to the dotted position the relay XS is picked up even though relay 3H is now de-energized. The picking up of this relay XS under this condition is entirely safe, because the treading of said east bound train upon the track circuit d places the signal 7 and 7^d in their stop condition, so that a west bound train will not enter the east end of single track section O. 70

The foregoing rather specific description is of one form of the invention and is selected solely by way of example and is not intended, in any manner whatsoever, in a limiting sense. Obviously, the invention can assume many different physical forms, is applicable in many different manners to many specifically different absolute-permissive-block systems, is susceptible of numerous modifications, and is intended to include in this application all such forms and modifications as come within the appended claims. 75

Having described my invention, I now claim:

1. In combination with a single track railway signaling system of the type in which a single track section is signaled for train movement in both directions and in which the signals are controlled so that the entrance of a train in one end of such single track section places all of the opposing signals in their stop condition and in which the first signal in the rear of such train is held at stop, the second signal is held at caution and the third signal is permitted to clear in accordance with the progress of such train, and of means for at times preventing such opposing signals assuming the stop position until the entering train has entered into the single track section a predetermined distance. 80

2. In combination with a single track railway signaling system of the type in which a track section is signaled for train movement in both directions and in which the signals are controlled so that the entrance of a train in one end of such track section places all of the opposing signals in their stop condition and in which the first signal in the rear of such train is held at stop, the second signal in the rear is held at caution and the third signal in the rear is permitted to clear in accordance with the progress of such train, and of means for varying the effective length of such track section. 85

3. In combination, a stretch of railway track, signals located at intervals for governing traffic through said stretch, a signal circuit for each signal, means for putting each signal to stop by the signal circuit for the signal next in advance, track circuits for the stretch including track relays for controlling said signal circuits, means for rendering each signal circuit ineffective to put to stop the signal next in the rear, and other means for rendering a particular signal ineffective to 90

put to stop the next signal in the rear thereof.

4. In combination, a stretch of railway track, signals located at intervals for governing traffic through said stretch, a signal relay

5 for each signal, means for controlling the continuity of the circuit for each signal relay by the signal relay for the next signal in advance, track circuits for the stretch including track relays for controlling said signal relays, means for rendering each signal relay ineffective to control the continuity of the signal relay for the next signal in the rear, and other means for rendering a particular signal relay ineffective to control the

15 continuity of the circuit for the signal relay of the signal in the rear thereof.

5. In a railway signaling system, in combination; a stretch of single track; a signal guarding the entrance to said stretch at each

20 end; intermediate signals located at intervals along the stretch for governing traffic in one direction; a polarized signal circuit for controlling each signal; control means associated with the signal circuit for each inter-

25 mediate signal for controlling the continuity of the signal circuit of the signal next in the rear; means for rendering said control means ineffective; and manually operable means for placing a particular intermediate signal

30 in its stop condition and rendering such signal ineffective to control the continuity of the signal circuit for the next signal in the rear.

6. In a railway signaling system, in combination; a single track railway divided into

35 track sections by passing sidings, a starting signal at each end of each section, intermediate signals along a track section for governing traffic in both directions, tumble-down circuits for each section for causing a signal

40 to put the next signal in the rear to stop, supplemental means for controlling the signals for one direction of traffic in accordance with the condition of the next signal in advance of such signal and the condition of

45 occupancy of the intervening track, and other means for placing a signal in the stop position without causing the next signal in the rear thereof to be put to stop.

7. In a railway signaling system, in combination; a single track railway divided into

50 track sections by passing sidings, a starting signal at each end of each section, intermediate signals along a track section for governing traffic in both directions, tumble-down

55 circuits for each section for causing a signal to put the next signal in the rear to stop, supplemental means for controlling the signals for one direction of traffic in accordance with the condition of the next signal in

60 advance of such signal and the condition of occupancy of the intervening track, and means for varying the length of trackway through which the tumble-down circuits are capable of causing one signal to put to stop

65 the next signal in the rear.

8. In combination, a stretch of railway track, signals located at intervals for governing traffic through said stretch, a signal relay for each signal, means for controlling the continuity of the circuit for each signal relay by the signal relay for the next signal in advance, track circuits for the stretch including track relays for controlling said signal relays, means for rendering each signal relay ineffective to control the continuity of the signal relay for the next signal in the rear, and means for varying the effective length of the stretch through which signals are controlled in the manner described.

9. The method of controlling the signals of single track railroads whereon signals are provided for governing traffic moving in both directions, which consists in normally controlling the signals of a single track section by control circuits of the absolute-permissive-block type, and in at times holding the signals governing the entrance to a portion of such single track section at stop and governing the signals of the remaining portion of such section by control circuits of the absolute-permissive-block type.

10. In combination, a stretch of railway track, signals located at intervals for governing traffic through said stretch, a signal relay for each signal, a tumble-down circuit arrangement comprising means for controlling the continuity of the circuit for each signal relay by the signal relay for the next signal in advance, track circuits for the stretch including track relays for controlling said signal relays, means for rendering each signal relay ineffective to control the continuity of the signal relay for the next signal in the rear, and means for intercepting the tumble-down circuit arrangement.

11. In a railway signaling system, in combination; a single track railway divided into track sections by passing sidings, a starting signal at each end of each section, intermediate signals along a track section for governing traffic in both directions, tumble-down circuits for each section for causing a signal to put the next signal in the rear to stop, supplemental means for controlling the signals for one direction of traffic in accordance with the condition of the next signal in advance of such signal and the condition of occupancy of the intervening track, and means for intercepting said tumble-down circuits.

12. The combination with a railway signaling system of the single track absolute-permissive-block type, in which the entrance of a train into one end of a single track section causes the signals governing the entrance of trains into the other end of said section to assume the stop condition, and in which an intermediate signal is employed to govern the movement of trains by an intermediate point; and of means for permitting switching moves to be made in said single track

section within the zone to said intermediate signal without blocking the entrance of trains from the opposite end of said single track section comprising; a manually operable lever, and means effective if said lever is moved to an abnormal position to cause said intermediate signal to assume the stop position and prevent the signals governing the entrance of trains into the other end of said 10 single track section assuming the stop position in response to entrance of a train into the single track section at said one end.

13. The combination with a railway signaling system of the single track absolute-permissive-block type, in which the entrance of a train into one end of a single track section causes the signals governing the entrance of trains into the other end of said section to assume the stop condition, and in which an 15 intermediate signal is employed to govern the movement of trains by an intermediate point; and of means for permitting switching moves to be made in said single track section within the zone to said intermediate 20 signal without blocking the entrance of trains from the opposite end of said single track section comprising; a track switch at said one end of said single track section, a switch machine, a switch stand, a dual control selector operatively connecting either said switch 25 machine or said switch stand to said track switch, and means controlled by said dual control selector for placing said intermediate signal in the stop position thus preventing 30 the entrance of a train at one end of said zone, and placing the signals governing the entrance of trains into the other end of said zone at stop when said dual control selector is moved to operatively connect said switch 35 stand to said track switch, said switching moves being made by train order and without obedience to said signals.

14. In a railway signaling system, in combination; a single track railway divided into 40 track sections by passing sidings, a starting signal at each end of each section, intermediate signals along a track section for governing traffic in both directions, tumble-down circuits for each section for causing a signal 45 to put the next signal in the rear to stop, supplemental means for controlling the signals for one direction of traffic in accordance with the condition of the next signal in advance of such signal and the condition of 50 occupancy of the intervening track, a stick relay near one of said intermediate signals which if energized places said one intermediate signal in the stop position and renders inactive the tumble-down circuit to put the next signal in the rear of said one signal to stop, a pick-up circuit for said stick relay including a manually operable contact and a contact closed if traffic conditions in advance of said one signal are favorable, and a stick circuit for said stick relay 55 60 65 70 75 80 85 90 95 100 105 110 115 120 125 130

including said manually operable contact and a front stick contact of said stick relay.

15. In a railway signaling system in combination; a single track railway divided into track sections by passing sidings, a starting signal at each end of each section, intermediate signals along a track section for governing traffic in both directions, tumble-down circuits for each section for causing a signal to put the next signal in the rear to stop, supplemental means for controlling the signals for one direction of traffic in accordance with the condition of the next signal in advance of such signal and the condition of occupancy of the intervening track, a stick relay near one of said intermediate signals which if energized places said one intermediate signal in the stop position and renders inactive the tumble-down circuit to put the next signal in the rear of said one signal to stop, a pick-up circuit for said stick relay including a manually operable contact in series with two contacts in multiple one of which is closed if favorable traffic conditions exist in advance of said one signal and the other of which is closed when a train is passing said one signal in the opposite direction to that in which said one signal governs traffic, and a stick circuit for said stick relay including said manually operable contact and a front stick contact of said stick relay.

In testimony whereof I affix my signature.
SEDGWICK N. WIGHT.
